REFRIGERATOR CASE

George J. Hopkins, Kendallville, Ind., assignor to
 McCray Refrigerator Company, Kendallville,
 Ind., a corporation of Indiana

Application June 10, 1933, Serial No. 675,253

3 Claims. (Cl. 312—138)

The present invention relates to refrigerator cases and more particularly to detachably secured sliding doors therefor of the character and type hereinafter illustrated and more particularly described.

The main objects of the invention are to provide a refrigerator case having one or more detachably inserted sliding doors; to provide sliding doors of the character above indicated, which when slid into their closed positions effect a substantially air-tight seal between the interior of the refrigerator and the exterior thereof; to provide doors of the sliding type which have means for effecting free and easy sliding; and, to provide a refrigerator case having sliding doors made of a material which is non-moisture absorbing and thus free from warping.

An illustrative embodiment of the invention is shown in the accompanying drawings, wherein: Figure 1 is a fragmentary front elevational view of the bottom portion of a pair of sliding doors for a refrigerator case, the doors being shown in their closed position;

Figure 2 is an enlarged sectional view of the lower sash and sill of the sliding doors of the refrigerator case on line 2—2 of Figure 1;

Figure 3 is a sectional view thereof on line 3—3 of Figure 2 and showing particularly the manner by which a substantially air-tight seal is effected between the interior of the refrigerator and the exterior thereof when the doors are in their closed position;

Figure 4 is a fragmentary front elevational view of one of the doors, a portion thereof being broken away and in section on line 4—4 of Figure 3;

Figure 5 is a fragmentary front elevational view of the top portion of the pair of sliding doors when in their closed position, the left-hand door being likewise indicated in dotted lines as the center of the opening prior to its insertion;

Figure 6 is an enlarged sectional view thereof on line 6—6 of Figure 5;

Figure 7 is a sectional view on line 7—7 of Figure 5, assuming the left-hand door is in the position indicated in dotted lines and in its detachably insertable position; and

Figure 8 is a sectional view on line 8—8 of Figure 7.

Referring to the drawings in which like parts are designated by the same numerals in the several views, a refrigerator case generally designated 1 is provided with an opening rectangular in shape to permit access to the interior thereof. This opening is provided with an upper sill 2

and a lower sill 3, preferably of hard or vulcanized rubber or of some other non-moisture absorbing material, and each sill is provided with a pair of spaced longitudinal tongues 4, 5, 6 and 7, here shown as integrally formed with the sill. 60 The lower tongues 4, 5 are each provided with a channel member 8, preferably of metal, molded integrally therein providing a track for door bearings hereinafter more particularly described. The channel bar 8 is composed of spaced substantially parallel sides and a connecting tread portion and the sides have divergent edge portions extending beyond the adjacent tongue and embedded in the sill at opposite sides thereof, as clearly illustrated in Fig. 2 of the drawings. 65 A longitudinally extending block 9 having a substantially central longitudinal guide rib 10 is disposed interjacent one pair of the longitudinal tongues and here shown as suspended between the upper tongues 6, 7. 70

A pair of doors generally designated 11, 12 whose frames are preferably of hard rubber, porcelain enameled steel or some other non-moisture absorbing material and having reinforcing cores, each have a lower sash 13, 14 and an upper sash 80 15, 16 and each sash is provided with a longitudinal groove 17, 18, 19 and 20 registering with its companion tongue 4, 5, 6 and 7 respectively when the doors are detachably inserted within the opening as hereinafter explained. One sash 80 of each of the doors is provided with a longitudinal slot 21, 22 here shown as in the upper sash of each door and substantially medial of its length. Each slot is adapted to register with the block 9 when it is desired to detachably insert the doors 80 within the opening as best indicated in Figures 5 and 7.

Each of the longitudinal grooves 17, 18 within the lower sash of each door is provided with a plurality of spaced ball bearing cups 23 preferably 05 of metal whose open peripheral edge is turned inwardly to retain the balls 24 therein which roll upon the track or channel member 8 and the inserted disc 25 during the sliding movement of the doors. The opposed faces of the ends of the 100 doors have cammed surfaces 26, 27 as best shown in Figure 3 for frictionally contacting each other and the ends of the case for sealing the opening of the refrigerator case when the doors are slid to closed position and a practical airtight seal 105 is thereby effected between the interior of the refrigerator and the exterior thereof.

As heretofore indicated, the doors may be detachably inserted to slidably fit within the opening one behind the other and seal the interior of the 110

refrigerator from the outside thereof when the doors are slid to closed position as is shown in Figures 1 and 5.

5 Detachable insertion of the doors within the opening is effected by first placing the door 12 adjacent the opening with its slot 22 in registration with the depending block 9 and lifting the door until it clears the track or channel member 8 when it may then be dropped onto the track and slid 10 thereon. Since the block and slot are in registration at only one point, sliding of the door retains it within the opening by means of the grooves in its upper and lower sash. The door 11 may be similarly detachably inserted within the opening 15 and slidably retained therein in a like manner. The method of insertion of the doors is best indicated in Figures 5 and 7 wherein the slot 21 of the door 11 has been placed in registration with the block 9 prior to dropping it onto its track 8 20 as is illustrated in Figure 2.

It is thus seen that a refrigerator case having a pair of non-warping detachably inserted sliding doors which provide a practical air-tight seal between the interior and exterior of the refrigerator when the doors are in their closed position has been herein shown and described and that means for effecting easy and free sliding of the doors is herein illustrated and described.

While but one specific embodiment of the several inventions has been herein shown and described, it will be understood that numerous details of the construction shown may be altered or omitted without departing from the spirit of this invention as defined by the following claims.

35 I claim:

1. In a structure of the class described, a case having an opening therein, the upper and lower sill of said opening each having a pair of spaced longitudinal tongues, one of said sills having a block secured interjacent one pair of said spaced

tongues, a pair of doors for said opening each having an upper and lower sash and each sash being provided with a longitudinal groove, one sash of each of said doors being provided with a slot adapted to register with said block whereby each door may be detachably inserted within said opening and slidably retained therein by means of said tongues and grooves.

2. In a structure of the class described, a case having an opening therein whose upper and lower sills are each provided with an integrally formed longitudinal tongue projecting beyond the surface of the sill, a metallic channel bar member composed of spaced substantially parallel sides and a connecting tread portion and embracing the tongue of the lower sill, whose edges are embedded in the sill and molded integrally therewith to form a track, the sides of the channel bar member being provided with divergent longitudinal edge portions embedded in the sill beyond the adjacent tongue, and a door for said opening whose upper and lower sashes are each provided with a longitudinal groove slidably registering respectively with the tongues of the upper and lower sills of the opening and receiving the said tongues. 100

3. In a structure of the class described, a case having an opening, the upper and lower sill of said opening each having a pair of spaced longitudinal tongues, one of said sills having a block 105 secured interjacent one pair of said spaced tongues, and a pair of doors for said opening each provided with a longitudinal groove at its top and bottom and having a slot adjacent one of the grooves adapted to register with said block 110 whereby each door may be detachably inserted within said opening and slidably retained therein by means of said tongues and grooves.
